UNITED STATES PATENT OFFICE.

JACOB RITTER, OF NEW YORK, N. Y.

CLASP.

SPECIFICATION forming part of Letters Patent No. 716,280, dated December 16, 1902.

Application filed October 1, 1902. Serial No. 125,456. (No model.)

To all whom it may concern:

Be it known that I, JACOB RITTER, a citizen of the United States, residing in New York, borough of Manhattan, and State of New York, have invented certain new and useful Improvements in Clasps, of which the following is a specification.

This invention relates to certain improvements in the clasps for chatelaines and other articles, for which Letters Patent were granted to me on July 8, 1902, No. 704,212, said improvements being designed with a view to simplify the construction of the clasp and permit its more convenient operation from the upper or front portion of the same, and for this purpose the invention relates to a clasp comprising a suspension-hook, a spring-clip attached at one end to the lower part of the hook and adapted by its resilience to retire from the rear leg of the hook, a laterally-movable cam plate or lever pivotally mounted upon the hook and carrying a cam device adapted to engage the spring-clip, and a face-plate for said hook, said lever being extended through a slot in the upper end of the suspension-hook or through the hook and front plate, so as to be operated from the upper front part of the clasp.

The invention relates, further, to certain details of construction and combinations of parts, which will be fully described herein-after and finally pointed out in the claims.

In the accompanying drawings, Figure 1 represents a front elevation of my improved clasp. Fig. 2 is a side elevation of the same. Fig. 3 is a front view of a modified form of the clasp. Figs. 4 and 5 are vertical transverse sections, drawn on a larger scale, of the clasp shown in Figs. 1 and 2, showing the spring-clip respectively in open and in locking position. Fig. 6 is a vertical transverse section of the clasp shown in Fig. 3 on line 6 6, Fig. 3; and Figs. 7, 8, and 9 are horizontal sections respectively on lines 7 7, Fig. 4, 8 8, Fig. 5, and 9 9, Fig. 6.

Similar letters of reference indicate corresponding parts.

Referring to the drawings, A represents an ordinary suspension-hook, such as is commonly used for suspending chatelaines or other articles. The lower front portion *a* of the hook is provided with a pivoted keeper or

eye C, from which the suspension-ring of the chatelaine or other article is suspended. To the lower front portion *a* of the suspension-hook A is riveted a spring-clip D, the backwardly-bent upper end *d* of which is serrated, said spring-clip being actuated by a laterally-movable cam-plate B, which is pivoted at its lower end at *s* to the lower main portion of the suspension-hook and provided with a cam *b*, that engages the spring-clip, the latter being provided with raised portions *b*², so as to permit the ready riding of the cam device upon the same. The upper end *b*' of the laterally-movable cam-plate B is extended through a slot *s*' in the upper end of the suspension-hook A to some distance above the same, so as to form a lever by which the cam-plate can be operated, the slot in the upper end of the suspension-hook serving for limiting the oscillating motion of the cam-plate. To the front portion of the suspension-hook is attached an ornamental front plate E, which is covered with leather E' or other suitable material. In place of extending the upper end of the cam-plate through the upper end of the suspension-hook above the same and the front plate it may be bent forward in the shape of a lip *e* and pass through coinciding arc-shaped slots *e*' in the upper end of the suspension-hook and the front plate, as shown in Figs. 3 and 6, the cam-plate being operated in one case by taking hold of the upwardly-projecting end *b*' of the cam-plate, while in the other case it is operated by taking hold of the forwardly-projecting end *e* of the same. When the plate is moved in this manner into locking position, its cam device engages the spring-clip and forces its serrated end *d* into engagement with the belt or other article which is placed between the spring-clip and the rear leg *a*' of the suspension-hook A. When the spring-clip is released by moving the cam-plate in opposite direction, the resiliency of the spring-clip causes the serrated end to retire from the rear leg of the hook, so as to permit the clasp to be readily removed from the belt or other article to which it is applied. The arc-shaped slot is of such size that the lateral motion of the cam-plate is limited thereby, so that when it is placed in one position its cam will engage the spring-clip and clamp the suspen-

sion-hook to the article from which it is suspended or release it therefrom when the cam-plate is moved in the opposite direction. The rear leg a' of the hook may be provided 5 with depressions d^2 , so that the belt or other article is firmly held between the serrated end of the spring-clip and the depressions d^2 , creating thereby a friction between the belt, suspension-hook, and spring-clip.

10 My improved clasp for chatelaines and other articles has the advantage that the cam-plate is arranged separately from the front plate and is operated from the upper or front end of the clasp, which permits the 15 easier operation of the clasp when the clasp heretofore patented by me is used, while it also simplifies the construction, and thereby cheapens the clasp.

My improved clasp is adapted for clasps of 20 large and small sizes for different articles—such as necktie-clasps, cuff and collar holders, &c.

Having thus described my invention, I claim as new and desire to secure by Letters 25 Patent—

1. A clasp, consisting of a suspension-hook, a spring-clip attached at one end to the hook

and having its opposite end provided with serrations, and a laterally-movable cam-plate pivoted to the lower front portion of said 30 hook and provided with a cam device adapted to engage the spring-clip, said cam-plate passing through a slot at the upper part of the suspension-hook to the outside of the same, substantially as set forth.

2. A clasp, consisting of a suspension-hook, a spring-clip attached at one end to the hook and having its opposite end provided with serrations, and a laterally-movable cam-plate pivoted to the lower front portion of said 40 hook and provided with a cam device adapted to engage the spring-clip, the upper end of said cam-plate passing through an arc-shaped slot at the upper end of the suspension-hook and front plate, substantially as 45 set forth.

In testimony that I claim the foregoing as my invention I have signed my name in presence of two subscribing witnesses.

JACOB RITTER.
